UNITED STATES PATENT OFFICE.

JESSE W. STRANGE, OF BLANCHARD, IDAHO.

DEVELOPING APPARATUS FOR PHOTOGRAPHIC PLATES.

Application filed February 2, 1921. Serial No. 441,887.

To all whom it may concern:

Be it known that I, JESSE W. STRANGE, a citizen of the United States, residing at Blanchard, in the county of Bonner and 5 State of Idaho, have invented a new and useful Developing Apparatus for Photographic Plates, of which the following is a specification.

This invention relates to apparatus for 10 use in developing photographic plates, one of its objects being to provide a simple and compact structure in which the plates can be placed readily after exposure and wherein they can be given a bath in developing fluid 15 without being exposed to light rays.

With the foregoing and other objects in view which will appear as the description proceeds, the invention resides in the combination and arrangement of parts and in 20 the details of construction hereinafter described and claimed, it being understood that, within the scope of what is claimed, changes in the precise embodiment of the invention shown can be made without departing from the spirit of the invention. 25

In the accompanying drawings the preferred form of the invention has been shown.

In said drawings

30 Figure 1 is a vertical longitudinal section through the device, a plate holder being shown in position therein in elevation.

Figure 2 is a plan view.

Figure 3 is a section on line 3—3, Figure 35 1.

Figure 4 is a section on line 4—4, Figure 1,

Referring to the figures by characters of reference 1 designates a casing of any desired proportions and open at the top, the 40 various joints of the casing being made light-proof, preferably by means of some improved connections such as shown at 2. The bottom of the casing may be provided with supporting knobs 3 while arranged 45 transversely within the casing near one end is a partition 4 slightly inclined, as shown in Figure 1 and provided with an opening 5 the area of which is greater than that of the plate to be developed. Between this partition 4 and one end of the casing 1 is a follower or backing strip 6 held normally 50 pressed toward the partition by bow strings 7 the intermediate portions of which are attached to the end wall of the casing 1 while 55 the end portions engage the strip 6. This follower strip works between guide strips 8

arranged on the partition 4 and extending toward the adjacent end of the casing 1, the space between the partition and the follower strip and between the guide strips 8 being 60 designed to receive a plate holder such as indicated generally at H and which holder can be of the usual construction.

The casing 1 is provided with a removable lid or cover 9 having a depending guard rib 65 10 adapted to fit into the space between the partition 4 and the far end of the casing 1 and to bear against said partition and the sides and said end wall of the casing. Furthermore felt or other soft material indicated at 11 can be interposed between the lid or cover and the walls and partition of the casing. This cover 9 may be fastened in position by any suitable means, such as spring clips 12 hingedly connected to the 70 walls of the casing and having engagement with lugs 13 upon the cover.

An opening 14 is formed in the cover and secured to the walls of this opening is a flexible closure 15 formed preferably of a 80 light-proof fabric which normally hangs within the casing 1 and has its lower end portion normally closed by a band 16 of elastic or the like. A lid 17 may be hingedly mounted on the cover 9 so as normally to 85 extend over the fabric 15 and the opening 14, this lid being fastened by means of a spring catch 18 as shown.

When it is desired to develop a plate the holder H containing the plate is inserted 90 through a slot 21 formed in the cover 9. This holder will thus enter between the partition 4 and the follower strip 6 and the said follower will press the holder firmly against the partition 4 as shown in Figure 1. 95 With the holder thus in place the shutter therein nearest the opening 5 and which has been indicated at S can be removed whereupon the plate nearest the opening 5 and which has been illustrated at P, will be free 100 to swing forwardly and downwardly through the opening 5. Before this action is taken, however, one hand of the user is inserted downwardly through the open lower end of the fabric closure 15 after 105 raising the lid 17 so that the hand will thus be in position to engage the plate as it tilts downwardly from the holder. The plate is then grasped and placed in the necessary baths which can be located in the structure 110 and after it has been developed is removed therefrom.

It will be obvious that by providing a structure such as herein described it is possible to quickly and efficiently develop plates without requiring a dark room.

5 5. What is claimed is:—

10 1. Developing apparatus including a casing, a partition extending transversely thereof and having an opening therein, a cover upon the casing having a slot for the reception of a plate holder, a follower within the casing for pressing a plate holder against the partition, said follower and partition cooperating to support the holder in an inclined position to release a plate by 15 gravity when a shutter is withdrawn from the holder, a flexible hand receiving portion depending from the top of the casing and having a normally closed inner end portion, and means within the casing for holding a 20 developing fluid.

25 2. Apparatus of the class described including a casing, an inclined partition therein provided with an opening, a spring pressed follower adjacent the partition, a cover detachably secured upon the casing and having an opening above the space at one side of the partition and a slot above the space at the other side of the partition, said slot constituting means for receiving 30 a plate holder insertable into the casing between the partition and follower, a light-proof flexible fabric secured within the opening in the cover, elastic means for holding said flexible closure normally gathered 35 adjacent its lower end said closure being

adapted to expand to receive the hands of the user when inserted into the casing, and a lid mounted on the cover and extending over said opening and the flexible closure suspended therein.

40 3. A developing apparatus including a casing, a cover thereon having a spaced opening and transverse slots, a lid normally closing said opening, a flexible closure secured to the walls of the opening and extending downwardly into the casing, elastic means for holding the lower end portion of the flexible closure normally gathered, said lower end portion being expansible by the insertion of a hand into the casing, an inclined partition extending transversely within the casing between the slot and opening, said slot constituting means for guiding a plate holder into position back of the partition, a spring pressed follower for engaging an inserted holder to press it against the partition and hold it in inclined position, said partition having an opening therein for the reception of a plate released by the withdrawal of a shutter from the holder, 45 and a tray within the casing and below the flexible closure.

50 55 In testimony that I claim the foregoing as my own, I have hereto affixed my signature in the presence of two witnesses.

JESSE W. STRANGE.
